UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

TARGET-PRACTICE VENDING MACHINE.

Application filed December 14, 1925. Serial No. 75,346.

The primary object of the present invention is to provide a machine, for use in connection with the sale of articles of merchandise, such as pieces of chewing gum, sticks of chocolate, cigarettes and the like, with coin-using means for target-practice, thereby to render interesting the operation by inducing the exercise of skill in the way of endeavor to cause a propelled coin to hit one of a plurality of prize-targets entitling the operator, when successful in the endeavor, to receive a prize in addition to the article paid for by the used coin.

Referring to the accompanying drawings—

Figure 1 is a perspective view of the machine;

Figure 2 is a broken section on an enlarged scale over Fig. 1, on line 2—2, Fig. 4;

Figure 3 is a section on line 3—3, Fig. 2;

Figure 4 is a section on line 4—4, Fig. 2;

Figure 5 is a rear view of the machine, with the casing-back removed;

Figure 6 is a section on line 6—6, Fig. 5;

Figure 7 is a view in front elevation of the device provided with the target-forming pockets, and

Figure 8 is a view of the same in rear elevation;

Figure 9 is a view like that presented in Fig. 8, but with parts removed to disclose details;

Figure 10 is a view in side elevation of the device illustrated in Fig. 7;

Figure 11 is a section on line 11—11, Fig. 8;

Figure 11^a is a perspective view of a pocket-forming detail;

Figure 12 is a plan sectional view on line 12, Figs. 7, 8 and 9;

Figure 13 is a broken view in section on line 13, Fig. 6;

Figure 14 is a section on line 14—14, Fig. 6, viewed in the direction of the arrows, and

Figure 15 is a partly broken view in section on the aforesaid line 14—14, Fig. 6, showing the coin-receiving drawer in plan.

The casing, which is preferably formed of metal and of general rectangular shape, has the lower part of its sides expanded forwardly to provide the upright section A, relatively narrow from back to front, and the wider base B, with a seating bed-plate b on the base, which is provided with a cover or ledge c fastened in place; and the section

A also has a cover a fastened in place. The back d of the casing is preferably a wooden sheet, as is also an interior back e for the section A, set to extend between its sides and to the cover a, near the forward edges of the 60 sides; the back e being preferably covered by a pane of glass f, forming the intervening space g. In the expanded base a drawer D, forming a coin-receptacle, is supported to be operated through the open face of the 65 base B, which is covered by a plate h secured in place by a suitable lock, indicated at i; and the drawer is shown to contain, near one end, three relatively narrow and shallow coin-receiving compartments, k, l 70 and m though the number thereof may be one or more, leaving the remainder of the drawer's interior a single larger compartment for the coin-receiving purpose.

On one side of the casing-section A, near 75 its upper end, is fastened a pair of plates secured together in spaced relation to form a coin-insertion slot-device 16 (Fig. 1), the rear plate having a projection 17 on its upper edge for guiding a coin 18 in inserting it into the slot to its seat in the bottom thereof, which slightly inclines upwardly to the discharge-end of the slot to cause the coin to be retained on its seat until driven therefrom through an opening in that side 80 of the casing to which the slot leads. Behind the coin-seat a driver 19 is provided, shown (Fig. 2) in its preferred form of a finger pivoted at its upper end between the two slot-forming plates to hang between 85 them and adapt it to be forcibly turned on the pivot, between rear and front limiting stops 20 and 21 in its path, to drive a coin ahead of it through the space between the back e and its glass cover f, as and for the 90 purpose hereinafter described.

At a side of the casing-section A, preferably as shown, opposite that carrying the slot-device 16, is secured to the face of the back e a target-device of the following-de- 100 scribed preferred construction:

A plate 22 is rigidly secured to the back e, in spaced relation thereto, by suitable flanges recessed in their outer edges, one of these flanges, shown at 23, projecting rearwardly from the outer edge of the plate and the other, shorter flange, 24, from the face thereof; these flanges being connected at their lower ends by a boss 25 presenting an inclined surface. Near its outer edge 105 110

the plate 22 contains a vertical series of circular holes 26, each affording a window for the purpose hereinafter described, these windows being marked 1, 2 and 3, respectively, as shown in Figs. 1 and 7; and in the edge of the plate 22 are shown to be formed three letters C, each relating to a window to indicate a center to be attained by the target-practice hereinafter described. On the back of the plate 22 is provided, beneath each window 1 and 2, a guide-lug 27 (Fig. 11). Against the under of the lowermost of these lugs bears the upper edge of the head of an approximately S-shaped plate 28 (Figs. 11 and 11^a), confined at its lower end between and seating in the recesses of the plate-flanges 23 and 24, where it covers and is spaced from the boss 25 to form a coin-passage 29 (Fig. 11) between them; and the back of the plate 28 has formed thereon a central, longitudinal fin-like guide-ridge 30.

As will be seen, the plate 28 forms with the back of the plate 22 a species of pocket 31, into which a coin may enter at the space 32 provided between the upper-end portion of the plate 28 and the back of the plate 22, and thence enter the pocket for discharge at the outlet 29.

The plate 28 is covered by a similar but somewhat longer plate 28^a, held in place between the flanges 23 and 24, with its upper end bearing against the uppermost lug 27; this plate being spaced from the plate 28 to form a pocket 31^a like the pocket 31 and opening to a coin-outlet 29^a, and having its inlet, at 32^a, between the back of the plate 22 and the upper-end portion or head of the plate 28^a.

A third plate 28^b, of substantially the shape of the plate 28^a but longer, covers the latter like it covers and is spaced from the plate 28, to provide a coin-inlet at 32^b to a pocket 31^b opening to a coin-outlet 29^b.

The plate is fastened at its opposite ends by screws to the back of the plate 22 (Fig. 8).

From the aforesaid coin-outlets 29 there extend similar chutes 33, preferably joined together, as shown, and leading, respectively, to the shallow drawer-compartments *k*, *l*, and *m*, for conducting thereto coins when released from the pockets; and the larger drawer-compartment D' receives coins that miss the targets, when impelled as hereinafter described, and drop, after being released, into that compartment, to which they are guided by an inclined runway 34.

It is desirable to retain the coins entering the target-pockets, and those missing the same, in view for inspection as to their being genuine, as against, say, slugs being used for the target-practice, hereinafter described. To this end a stop is withdrawably provided at each window 26 and at the entrance to the drawer-compartment D' where

the glass-covered casing-section A communicates therewith. The stop-means for the window comprise a slender bar 35 having similar stop forming prongs 35^a projecting in suitably spaced relation from its inner edge, whereby with the bar pivotally supported at its ends, as represented in Figs. 8, 9 and 10, on the back of the plate 22, the prongs will normally extend into the windows (Fig. 12), to which position, when withdrawn therefrom, they are returned by a spring 36 bearing against the bar. For working the bar 35 to withdraw the stops 35^a, it is connected, at a lug 37 projecting at an angle from the bar (Fig. 5), by a link 38 with a rod 39 journaled at its opposite ends centrally in the casing-cover *a* (where it carries a knob 39^a or handle) and in a lug 39^b at the bottom of the section A. For arresting, for the inspection purpose, coins on their way to the drawer-compartment D', a stop-blade 40 (Fig. 14) is pivoted near one end to the under face of the ledge *c* and is resiliently held, by a spring 40^a, to close the coin-passage at the end of the runway 34; and to withdraw this stop a link 40^b connects it eccentrically with the lower end of the rod 39.

For a purpose hereinafter described, a button 41 is provided on the face of the back *e* of the casing-section A adjacent each entrance to a target-pocket at "C," the button being preferably of rubber to render it resilient.

The machine is intended, more particularly, for use in the store of a merchant who sells such articles as are to be delivered by him to customers operating the machine, which should therefore be placed and secured, as on the counter, in position conveniently accessible to the customers. For the following explanation it may be supposed that the article to be delivered by the merchant to the customers for the price of the used coins, is chewing-gum.

To operate the machine, a coin 18 representing the purchase price of a piece of the gum is inserted edgewise into the slot 16, whereupon the user, with a finger and preferably his thumb, strikes the driver 19 with a forcible blow in the endeavor to cause the impelled coin to enter one or the other of the pockets. In the event of failure in that behalf, the coin drops through the space between the glass *f* and back *e* upon the runway 34, and is arrested by the finger 40 to remain in view through the glass *f* until released to the drawer; and the user is thereupon entitled to receive a piece of chewing gum, to be delivered to him by the merchant over the counter. Should the impelled coin strike the target, by entering the uppermost pocket, that success will entitle the customer to a prize of greater value than that of a single piece of the

gum—maybe two or more pieces of the same to be delivered by the merchant; and entry of the coin into the intermediate pocket by striking that target, entitles him to a 5 prize of still greater value; and so on throughout the number of target-pockets provided, which may, however, be only one or any desired number more than one, denoting prizes of any desired character and 10 of increasing value.

It is to be observed, however, that there can never be a miss, each operation entitling the operator to receive the article of the value represented by the coin, 15 whether or not he fails to strike the target, the purpose of which is to induce patronizing the machine by rendering its operation so attractive as to incite practice therewith to attain a degree of skill that will enable 20 the operator to hit a target with an impelled coin more or less frequently.

The buttons 41 are provided to tend to guard accidental entry of the impelled coin into a prize-pocket, by deflecting it to the 25 runway 34, thereby increasing the difficulty of the attainment and enhancing the degree of skill required therefor.

Coins arrested for inspection at the windows and at the end of the runway may 30 be released by turning the rod 39 to withdraw the stops 35^a and 40 from obstructing their entry, in the one instance, from each 35 of one or more of the pockets retaining a coin at a window 26, into the proper shallow drawer-compartment, and in the other instance into the drawer-compartment D'.

It will be observed that a coin released from the window of the uppermost target, having entered the same edgewise through 40 the inlet 32^b, runs flatwise along the fin 30 of the plate 28^a through the pocket to the outlet 29^b, whence it runs through the chute 33 leading from that outlet into the proper drawer-compartment; and the same 45 occurs to a coin released from the window of the intermediate or the lowermost target-pocket, in the last-named of which, however, the coin is guided to its outlet 29 and chute 33 by the inclined surface of the 50 boss 24.

I realize that considerable variation is possible in the details of construction thus shown and described, and I do not intend to limit my invention thereto except as 55 pointed out in the appended claims, by which it is my intention to claim all the novelty inherent in my invention as broadly as permissible by the state of the art.

I claim:

60 1. A machine of the character described, comprising a casing having its lower portion equipped with a plurality of coin receptacles, said casing being provided above said receptacles with a glass front and an inner

wall separated by a narrow space from said glass front, an intervening member between said wall and glass front presenting a runway at the lower portion of said space which leads to one of said coin receptacles, a plurality of coin-pockets disposed one above 70 the other within said space near the upper portion of the casing and disposed to permit the coins which miss said pockets to drop upon said runway, chutes leading from said coin-pockets to the other coin receptacles, a slot extending through the side of the upper portion of the casing opposite said coin-pockets and affording a seat for an inserted coin, and a driver associated with said slot adapted to impel a coin horizontally 75 through the upper portion of said space towards said pockets.

2. A machine of the character described, comprising a casing having a base containing a plurality of coin receptacles and having an upright section rising from the rear portion of said base, said upright section having a glass front and being provided with an inner wall separated by a narrow space from said glass front, an intervening member within said space near one lateral wall of the casing, said intervening member being equipped at its upper portion with a plurality of coin-pockets and presenting below said coin-pockets a vertical edge-portion 85 and a lateral runway across the lower portion of said space leading to a coin receptacle, chutes leading from said coin-pockets to the other coin receptacles, a slot through the lateral wall of said casing opposite said coin-pockets and an associated seat for an inserted coin, and a driver associated with said seat adapted to impel a coin across the upper portion of said space towards said coin-pockets. 90

3. A machine of the character described, comprising a casing having a base-portion containing a plurality of coin receptacles placed side by side, said casing having an upper section rising from the rear portion 100 of the base and provided with a glass front and with an inner wall separated by a narrow space from said glass front, an intervening plate in said space adjacent one side of the casing, a plurality of coin-pockets in the rear of the upper portion of said plate, said plate presenting a vertical edge and a runway across the lower portion of said space leading to a coin receptacle, studs in said space guarding the entrances to said 110 coin-pockets, said space being otherwise unobstructed, a coin-slot extending through the casing wall opposite said coin-pockets and a coin-seat associated therewith, and a driver adjacent said coin-seat adapted to impel a coin across the upper portion of said space towards said pockets. 115

FRED L. MILLS.
